HYDRAULIC PRESSURE EXCHANGE PUMP

Leon P. Deackoff, Watertown, Mass., assignor to Manton-Gaulin Manufacturing Company, Inc., Everett, Mass., a corporation of Massachusetts

Application April 6, 1956, Serial No. 576,641

7 Claims. (Cl. 103—152)

This invention relates to high pressure pumps, and more particularly to pumps of the hydraulic pressure exchange type in which a product fluid is pumped through the medium of a separate pumping fluid.

A primary object of the invention is to provide a pump capable of handling corrosive and erosive muds, slurries and solutions at high temperatures and/or pressures and at high capacities. It is a further purpose to provide a pump which can handle such product fluids far more effectively and economically than is possible through the use of conventional reciprocating, rotary or centrifugal types. This is made possible by reason of the elimination of plungers, stuffing boxes, plunger packing, valves and other items common to the aforesaid more conventional pumps which require excessive maintenance when handling product fluids of an abrasive nature. An hydraulic pressure exchange pump of the type described herein overcomes these difficulties since the trouble-producing product fluid is never in contact with any closely spaced, relatively moving surfaces where the abrasive or corrosive nature of the product fluid can cause high rates of wear.

While pumps of the type to which this invention appertains employ a diaphragm or membrane to isolate the product fluid to be pumped from the pumping fluid and other parts of the system, they are not to be confused with the conventional reciprocating diaphragm pump of relatively low capacity and pressure, working with a short stroke and producing widely pulsating discharge pressures. On the contrary, the pumps of this invention are capable of pumping capacities of almost any practical requirement, up to several hundred gallons per minute at pressures of over 1000 p.s.i. being readily obtainable, for example, and the discharge pressure is uniform and steady. It is often very desirable to supply a fluid at high pressure for processing, as to an autoclave, for example, but because the maintenance of conventional pumps when handling abrasive materials is so uneconomical, compromise is usually made with respect to the operating pressure. With a pump such as here described, it becomes unnecessary to accept this compromise.

The principle of hydraulic pressure exchange pumps of the type to which the invention is directed is generally well known. Basically, a non erosive pumping fluid, such as an hydraulic or lubricating oil, is transferred between a reservoir and a pressure cylinder. The latter employs a flexible membrane dividing the cylinder into separate pumping fluid and product fluid chambers. Product under a low head or pressure is supplied through an intake check valve to the product chamber and leaves the chamber through a discharge check valve. On the pressure stroke of the pumping cycle, hydraulic oil is pumped by a conventional pump from the reservoir into the cylinder, flexing the separating membrane and displacing the product fluid from its chamber and out through the discharge check valve. On the suction stroke, the hydraulic oil is permitted to return freely to the reservoir through

a by-pass, being displaced from the pressure cylinder by the product fluid under the aforesaid low pressure. In order to avoid the intermittent pumping action of this basic system, two or more pressure exchange cylinders 5 and their associated pumping fluid systems are connected in tandem, so that while one is on the intake stroke, another is on its discharge stroke. By controlling the overlap of the operating cycles, the effect of output pressure changes in one pressure cylinder, during transition from 10 pumping to intake strokes and vice versa, can be compensated for by another pressure cylinder. Wide pulsations from practically zero pressure to the maximum desired, as would occur in the single cylinder type, are thus avoided.

Notwithstanding the foregoing arrangement for staggering the pumping cycles of a number of pressure exchange cylinders, whereby the pressure pulsations are considerably reduced, prior pumps nevertheless are still subject in many instances to substantial pulsations which 20 are objectionable for many reasons. One of the principal causes for these pulsations in prior equipment is due to hydraulic hammer in the transition from intake to discharge strokes in the several hydraulic pumping fluid systems.

25 It is accordingly an object of this invention to provide a practical pump which is remarkably free of appreciable pulsation, and wherein the discharge pressure is remarkably smooth and uniform at whatever setting is selected within the available operating range. To this end, pumps 30 of the present invention employ relatively large pressure exchange cylinders and correspondingly slow rates of cycling. Furthermore, the cycling of these pressure exchange cylinders is accomplished by means of a novel pumping fluid control system, including the conduiting, 35 valving and sequencing control of those valves, whereby any tendency toward hydraulic hammer is obviated and uniformity of the resultant discharge pressure is obtained in a much more efficient and effective manner than heretofore. This will be brought out more fully hereinafter 40 in connection with the description of an embodiment of the invention illustrated in the accompanying drawings, wherein:

Fig. 1 is a flow diagram of a pressure exchange pump 45 in accordance with the invention, the pump illustrated employing two pressure exchange cylinders;

Figs. 2 and 3 are front and side elevational views, respectively, of the pressure exchange cylinders and associated product fluid check valves of the pump in Fig. 1;

Fig. 4 is an enlarged, fragmentary view in longitudinal 50 section through one of the cylinders shown in Figs. 2 and 3;

Fig. 5 is a side elevational view, partly in section and on an enlarged scale of one of the product check valves shown in Figs. 2 and 3;

55 Fig. 6 is a diagrammatic representation of an air operated valve and solenoid operated pneumatic control valve of the type employed in the invention;

Figs. 7, 8 and 9 are top plan, side and end elevational 60 views, respectively, of the hydraulic pumping fluid system and control cabinet; and

Fig. 10 is a schematic wiring diagram of the control circuit.

Referring to the flow diagram of Fig. 1, the hydraulic 65 pressure exchange pump comprises two pressure exchange cylinders 20, 20'. As previously mentioned and as will appear more fully hereinafter, each of these cylinders is provided with a flexible membrane or diaphragm dividing their respective interiors into a pumping fluid chamber and a product fluid chamber. The latter is connected in each case by suitable conduits 22, 22', respectively, to check valve assemblies 24, 24'. These in

turn are joined by common inlet and discharge manifolds 26, 28, respectively. The aforesaid pumping fluid chamber of each cylinder is connected to separate pumping fluid systems by suitable conduiting. Inasmuch as these are identical, the description of one will suffice here, it being understood that corresponding components of the other system are designated by a prime on the respective reference numerals.

High pressure conduit 30 connects the pumping fluid chamber of cylinder 20 to the discharge of a positive displacement rotary pump 32. The latter is supplied with an hydraulic or lubricating oil through an intake pipe 34 from a reservoir 36. As will appear presently, pump 32 and its counterpart 32' are connected to a common shaft and driven continuously by a single motor so that each is constantly pumping fluid at its discharge port whenever the system is in operation. A check valve 38 is connected into the high pressure piping 30 between the pump 32 and cylinder 20, this valve being arranged to limit flow of the hydraulic pumping fluid from the pump toward the cylinder. At either side of valve 38, by-pass or return lines 40, 42, are likewise teed into conduit 30 and these lines both discharge back into reservoir 36. By-pass lines 40 and 42 are provided with fluid motor operated return valves 44, 46, respectively. These valves are biased to a normally closed position and are opened by a fluid motor device 60. This is operated by pneumatic or hydraulic pressure, e.g. compressed air, water or oil, acting on the operating piston or diaphragm of the motor device of the respective valves. An additional by-pass line 48 is teed into the high pressure pipe 30 between pump 32 and check valve 38, and is provided with a manually operable valve 50. Fluid motor operated valves 44, 46, are operated cyclically, as will be described presently, to produce a reciprocating flow of hydraulic pumping fluid to and from cylinder 20 in order to effect the pumping of the product fluid. Low and high level float switches 52, 54, respectively, are mounted in reservoir 36 and these switches control the operation of valves 44, 46, through appropriate electrical control means described hereinafter.

Referring now to Fig. 6 of the drawing, there is illustrated diagrammatically the arrangement whereby control of return valve 44, for example, is effected. An identical arrangement is used for each of the other return valves 44', 46 and 46'. As mentioned above, valve 44 is normally biased to closed position by suitable spring means and the valve rod 56 is secured to the diaphragm 58 of the fluid motor device 60. In the example specifically illustrated in the drawings, the fluid is assumed to be air and this is delivered under pressure to fluid motor device 60 through conduit 62 from a three-way solenoid operated metering or control valve 64 of conventional construction. A supply line 66, having a manually set metering or restricting valve 68, therein, delivers compressed air to control valve 64 from a storage tank. Admission of air into line 62 from control valve 64 is normally blocked by a balanced plunger 70 which reciprocates within the control valve. Upon energization of solenoid 72, piston 70 is moved to a position to permit air to flow through line 62 into the operating chamber of fluid motor device 60 and thus open valve 44. The rate at which air enters, and thus the rate at which valve 44 is actuated, is controllable by means of the metering valve 68 in the supply line 66. Upon deenergization of solenoid 72, piston 70 is returned to its original position by spring means, and air in fluid motor device 60 is bled off to atmosphere through an adjustable bleed orifice 74 in control valve 64.

The physical arrangement of the various pumping fluid components described hereinabove is shown in Figs. 7 through 9. As will be seen in these views, the various components are mounted upon a base or pedestal 76. Included on this pedestal is an electric motor 78 which

drives, through conventional V-belt and pulley means 80, a shaft 81 which serves as a common drive shaft for both pumps 32, 32'. Control cabinet 82 houses the various electrical controls for the pump and is likewise mounted on the base.

Details of the construction of the pressure exchange cylinders are shown in Figs. 2 through 5. The size of these cylinders determines the displacement capacity of the system on each "pumping" stroke and consequently they may be quite large. For a unit having a capacity of 120 g.p.m. at discharge pressures up to 2000 p.s.i. for example, each cylinder is approximately 7 feet long and has an inside diameter of 7½ to 8 inches. Referring to Figs. 2 and 3, cylinders 20, 20' are mounted upon a base 83 in side-by-side relation. Also mounted on the base are the respective product fluid check valve assemblies 24, 24', which are interconnected by the inlet manifold 26 and the discharge manifold 28. Each check valve assembly 24, 24', is likewise connected through conduits 22, 22' (Fig. 3) to the base of the respective pressure exchange cylinders. At the upper ends of the cylinders, the hydraulic pumping fluid conduits 30, 30', are connected into the cylinders through suitable pipe T's to which pressure gauge lines are also run from gauges 84, 84'. Each of the cylinders is provided with an automatic, float type air vent 85, 85', and manually controlled vents 86, 86'. A system indicating panel P is suspended from the cylinders, this panel being electrically connected through suitable multiconductor cabling 93 to the control circuits in control panel 82 on the hydraulic pumping fluid system pedestal 76 (Fig. 8).

In Fig. 4 the interior construction of one of the pressure exchange cylinders is illustrated. This consists of a high pressure cylindrical outer shell 87 having end caps 88 bolted to it. Shell 87 is lined throughout with a neoprene sleeve 89. At the ends, the sleeve is squeezed between the respective end caps 88 and the shell where it serves as a gasket. Suspended within the cylinder is a diaphragm bag assembly 90 which in this instance is generally cylindrical, being only somewhat shorter in length and slightly smaller in diameter than the interior of the cylinder. The bag is preferably constructed of fabric reinforced neoprene sheet material and is quite flexible. At its upper end, this bag assembly is clamped by means of bands 92 to a cylindrical metal plug or top holder 94 which is apertured to permit passage therethrough of conduit 30 by which hydraulic pumping fluid is transferred to and from the interior of the cylindrical bag 90. At the lower end, a similar arrangement (not shown) is provided except that there is no axial passage through the bottom plug. There is thus provided an enclosed hydraulic pumping fluid chamber which serves to isolate such fluid from the product fluid which surrounds the bag in cylinder 20. Due to the flexibility of the walls of bag 90, this readily collapses and expands in accordance with the pressures on either side of its wall. In order to facilitate such flexing of the bag without subjecting it to strain, the lower bag holder or plug carries a tube which projects axially upwardly within the bag and telescopes about a downwardly projecting axial tube 96 constituting a continuation of the conduit 30. Tube 96 is provided internally with perforations 98 to permit transfer of pumping fluid to and from the bag 90. These perforations are located above the lower telescoping tube and are not interfered with in the course of slight axial shifting of the two tubes which takes place during a pumping cycle. This telescoping arrangement helps to maintain the diaphragm bag assembly 90 centrally located in the pressure cylinder.

Vent tubes 98, 100, at the upper end of cylinder 20 lead to the automatic and manual air bleed valves 85, 86, respectively. At the lower end of the cylinder 20, a drain tube 102 is also provided and this is normally closed by a suitable valve, not shown.

Details of one of the product fluid check valves 24 are shown in Fig. 5. This is of relatively standard high pressure construction employing ball checks 104, 106, at the inlet and discharge sides, respectively, of conduit 22 which leads to the interior of the cylinder 20.

Description of the pumping cycle

The operating sequence of the pump takes place as follows. Assuming that the motor 78 is running and pumps 32, 32', are delivering hydraulic pumping fluid, and further that the reservoir 36 is filled to a point where its high level switch 54 has been actuated, i.e., closed, while reservoir 36' is at its low level limit and switch 52' thereof has been closed, valves 44, 46, are closed, while valves 44', 46', are open. It is also assumed that the manually controlled pump by-pass valves 50, 50', are closed. At this point, diaphragm bag 90 of cylinder 20 is fully collapsed and the cylinder around the bag is filled with product fluid which has been delivered under low pressure from inlet manifold 26 through check valve 24. At this same time, the corresponding diaphragm bag 90' in cylinder 20' is fully expanded and most of the product fluid has been displaced from this cylinder by the expanded bag. Cylinder 20 is thus ready to start its discharge stroke while cylinder 20' is beginning its intake stroke.

Pump 32 delivers oil from reservoir 36 into cylinder 20, displacing the product through its product check valve 24 and delivering it under pressure to manifold 28. Pump 32' of course continues to deliver hydraulic pumping fluid but since the pump return valve 44' is open, this fluid is diverted back into the reservoir through by-pass line 40'. Also since the cylinder return valve 46' is now open, pumping fluid in the expanded diaphragm bag 90' of cylinder 20' is displaced by collapse of this bag owing to product fluid coming in through check valve 24' under a low head. Check valves 38, 38' at all times prevent any reverse flow of fluid to their respective pumps from the diaphragm bags.

At the end of the pumping stroke of cylinder 20, the low level switch 52 in reservoir 36 is closed. When this occurs valves 44, 46, open and valve 44' closes. At this point, reservoir 36' should now be filled to a point where its high level switch 54' has been closed, and this will act to close cylinder return valve 46'. No more hydraulic pumping fluid can therefore be expelled from cylinder 20'. In case high level switch 54' was not actuated and valve 46' did not close, an interlocking circuit in the electrical control system is energized and a "no delivery" condition exists at the discharge manifold 28 until switch 54' closes valve 46'. Assuming however that the system is operating properly and that the level in reservoir 36 has now reached its upper limit, pump 32' now begins to deliver hydraulic fluid to its cylinder 20' and product fluid continues to discharge under pressure at manifold 28.

Since valves 44, 46 have now been opened, fluid delivered by pump 32 is by-passed through pump by-pass line 40 and pumping fluid previously delivered to cylinder 20 is returned to reservoir 36 through by-pass line 42, being displaced from cylinder 20 by the incoming product fluid. When pump 32' has reduced the level of fluid in reservoir 36' to a point where the low limit switch 52' is closed, valves 44', 46' are opened and valve 44 of the alternate system is closed. Assuming that the fluid returned to reservoir 36 has reached the proper high level and actuated switch 54, valve 46 closes. One complete pumping cycle has now been completed. Again, however, if the level in reservoir 36 failed to rise to the proper point, valve 46 is not closed and a "no delivery" condition exists until that valve does close. As will be explained presently, provision is made to give a warning signal to a pump operator should such condition arise.

The manually controlled by-pass valves 50, 50' are adjustable to vary the pump output capacity at manifold

28 within the design limits of the equipment. It will be noted that the stroke of the pump is not affected by the adjustment of valves 50, 50'. The stroke is equal to the quantity of oil between the low and high levels 5 in reservoirs 36, 36'. This is easily adjustable by varying the setting of the low and high level switches 52, 52', 54, 54'. The maximum volume of the stroke is of course governed by the design of the pressure cylinder.

By properly controlling the sequence of operation of 10 valves 44, 44', 46, 46', the discharge pressure at manifold 28 may be kept uniformly steady while the system is in operation. As has previously been mentioned, these valves are spring biased to a normally closed position and are moved to an open position by fluid motor means under 15 the control of a control valve 64, the rate of operation of these valves is vital in eliminating hydraulic hammer. It is for this reason that the fluid metering provision previously described is supplied so as to permit control of the rate at which the actuating fluid is delivered to the 20 operating diaphragms or pistons of the valve motor devices, or is bled off therefrom.

Referring again to the diagram in Fig. 1 and to the 25 description of an operating cycle of the pump just described, toward the end of the pumping stroke of cylinder 20, cylinder return valve 46' closes when high level switch 54' is actuated. The closing of valve 46' is not critical, therefore no restriction is used on the fluid outlet 74 of its associated three-way solenoid valve 64. At this point in the cycle, valves 44, 46, are still closed. However, when low limit switch 52 of reservoir 36 is closed 30 at the end of the pumping stroke, valves 44, 46, open at a previously determined speed, being controlled by the rate at which air or other fluid is admitted to their respective diaphragms through their respective three-way 35 solenoid valves 64. In practice, valve 46 is made to open slightly faster than valve 44. This is essential so that check valve 38 does not slam shut. By opening valve 46 slightly faster than valve 44, the flow through valve 38 is decelerated at a controlled rate preventing this valve 40 from slamming and causing hydraulic hammer. Valve 44' also closes during this phase of the cycle, its closing rate being restricted by the metering valve 68 of its associated control 64. This closing rate is balanced against the speed at which valves 44, 46 are opened. During the transition 45 from one stroke to the other, therefore, hydraulic oil is pumped simultaneously for a short period of time from reservoir 36 and reservoir 36' into each of the respective pressure cylinders, and thus there is maintained a constant pressure of the product at the discharge manifold 28. As 50 in the case of valve 46', the closing of the valve 46 at the end of the intake stroke is not critical and the rate is not controlled therefore.

The problems of getting smooth, uniform pressure discharge which exist at an output capacity of three gallons 55 per minute, for example, are completely different from those at 25 gallons per minute. At the latter capacity, a gradual transition such as is accomplished by the just described metering of the valve actuating fluid is essential and this becomes all the more vital at higher capacities such, for example, as 200 gallons per minute. The 60 system just described makes it possible to attain capacities of this order without the difficulties which have been inherent in previously known pressure exchange pumping systems.

Description of the electrical control circuit

Proper sequencing of valve operation as just described 65 is accomplished by means of the electrical control circuit illustrated schematically in Fig. 10. This control circuit also serves to give adequate visual and aural warning of 70 failures in the pumping system and to protect the hydraulic circuits from damage in the event foreign fluids work their way into the hydraulic system.

Referring to Fig. 10, the system consists basically of 75 three mechanical latch relays 110, 112, 114. Relay 110,

when energized by low level switch 52, opens valve 46 by energizing solenoid 72 of the respective pneumatic control valve 64. Relay 112, when energized by low level limit switch 52', opens valve 46' by energizing the corresponding solenoid 72' of its pneumatic control valve. Relay 114, when energized by the low level switch 52, opens valve 44 and allows valve 44' to close; when energized by the corresponding low level switch 54' of the other system, relay 114 opens valve 44' and closes valve 44. Thus one or the other, but never both, of valves 44, 44', is always open.

In the event that valves 46, 46', are open simultaneously (this will happen any time a reservoir fails to fill properly at the end of the intake stroke of its respective system) relays 116, 118, are simultaneously energized, completing a circuit from terminal 7 of a photoswitch 120 through the respective contacts 122, 124, to the ungrounded side of horn 126, sounding the horn to indicate "no delivery." As soon as either valve 46 or 46' is closed, the horn will stop sounding; and when the respective cylinder return valve 46, 46', on the side which is on pumping stroke closes, pumping by that system will resume.

In the event that both low level switches 52, 52', are closed simultaneously, relays 128, 130, will be simultaneously energized. These carry contacts 132, 134, respectively, each set of which is in a circuit between the "hot" side 136 of the power mains and the ungrounded side of the operating coil of a pump motor control relay 138. Thus it will be seen that should both relays 128, 130 be energized simultaneously, breaking both power circuits to relay 138, the latter is deenergized and interrupts the power to the pump motor 78 and motor push button circuit. This deenergizes the pump motor push button circuit, stopping all pumping. If this happens, it is necessary to restart the pump motor manually by depressing the start button 140.

The photoswitch level controller 120 contains a normally closed and a normally open contact. Probes 142, 142' (see Fig. 8) are placed in the respective hydraulic pumping fluid reservoirs 36, 36', and so long as the probes are not in contact with a conducting fluid, terminal 1 of the photoswitch 120 is "hot" providing a power source for the pump motor push button circuit through control relay 138. However, when any of the probes comes in contact with a conducting liquid, terminal 3 of the photoswitch 120 becomes energized and terminal 1 becomes de-energized. In this condition a "telltale" light 144 comes on and horn 126 sounds a warning. The horn will also be energized through this circuit for approximately 30 seconds after the control circuit is first energized by closing of relay 146 until the tube in the photoswitch 120 warms up and starts conducting, breaking the alarm circuit and energizing the motor push button circuit as previously described. Relay 146 is a single pole relay which simply holds the control system energized after the "start" push button 148 is depressed and until the "stop" button is pushed.

Telltale lights similar to probe lights 144 are associated with each of the high and low level pumping fluid switches 52, 52', 54, 54', as well as with each of the bypass valves 44, 44', 46, 46'. Additionally there is a light indicating power delivered to the control circuit and one indicating operation of the pump motor, as well as of energization of one of the probes 142 as previously mentioned. To save complicating the wiring diagram, the return circuits to each of the several indicator lights is omitted but the circuitry is conventional and will be readily understood. Detailed explanation therefore is unnecessary. All of these lights are placed on the indicator panel P (Figs. 2 and 3) and are connected to the control circuit by the multiconductor cable 93. The lights are appropriately positioned on the indicator panel in conjunction with a combined pump flow and electrical control diagram similar to that in Fig. 10 of the drawings, whereby the pump operator is enabled to check the sys-

tem readily for proper operation and to locate the difficulty quickly in case of malfunction.

What is claimed is:

1. An hydraulic pressure exchange pump for a product fluid to be pumped, comprising two pressure exchange cylinders having flexible diaphragms therein dividing each into product fluid and pumping fluid chambers, respectively; a separate pumping fluid system connected to each of the latter and a common product fluid system connected to the product fluid chambers of both cylinders; control means for operating said pumping fluid systems in tandem so that while one of said pressure cylinders is in its discharge stroke, the other is in its intake stroke; said product fluid system including inlet and discharge manifolds, and check valves operatively associated with each cylinder permitting product fluid under low pressure to enter the respective cylinders from said intake manifold during the intake stroke and to be displaced into said discharge manifold during discharge stroke, respectively, of the cylinders but preventing reverse flow in said manifolds; each of said separate pumping fluid systems being identical and including a fluid reservoir, a positive displacement pump which delivers fluid therefrom continuously, a pump conduit connecting the pump output with the pumping fluid chamber of its respective cylinder, a check valve in said conduit limiting flow in a direction toward said chamber, return lines connected into said pump conduit at either side of said check valve and leading back to the reservoir, one of said return lines constituting a pump by-pass and having a normally closed pump return valve therein, the other line constituting a cylinder return line and having a normally closed cylinder return valve therein; fluid motor means for actuating said return valves to open position; said pumping fluid control means including means responsive to predetermined high and low fluid levels in each reservoir; said low level responsive means in one reservoir being adapted, when the fluid level therein reaches the predetermined low level, to cause both said return valves in its system to open and the pump return valve of the other pumping system to close; said high level responsive means in said reservoirs being adapted, when the fluid level therein reaches the predetermined high level, to cause the cylinder return valve of the respective system to close; and fluid metering means operatively associated with each of said fluid motor actuated return valves to regulate the speed of operation thereof, said metering means balancing the rate of opening of both return valves of a first system, as the latter approaches the end of its discharge stroke, with the rate of closing the pump return valve of the other system, as the latter starts its discharge stroke, so as to maintain a constant discharge pressure of the product fluid, said metering means likewise retarding the rate of opening of the pump return valve of said first system with respect to the rate of opening of its associated cylinder return valve during transition from discharge to intake stroke in each system.
2. An hydraulic pressure exchange pump as defined in claim 1, wherein each of said pumping fluid systems includes a manually controlled by-pass valve in parallel with said fluid motor actuated pump return valve which is adjustable to set the product fluid discharge pressure of the pump.
3. An hydraulic pressure exchange pump as defined in claim 1, wherein said pumping fluid system pumps are driven simultaneously by a single electric motor.

4. An hydraulic pressure exchange pump as defined in claim 3, wherein said pumping fluid control means includes an electric circuit and a source of power for energizing said circuit, a first relay operatively associated with each of said low level responsive means, respectively, and energized by said power source whenever the fluid in said reservoirs is below the predetermined, low level, a pump motor control relay, each of said first relays having normally closed contact points completing a circuit from

said power source to said pump motor control relay independently of the other of said first relays when deenergized but breaking its respective circuit to said pump motor control relay when energized, whereby said latter relay is deenergized whenever the fluid level in both said reservoirs drops below said predetermined low level.

5. An hydraulic pressure exchange pump as defined in claim 4, which further includes an interlock relay operatively associated with each of said return valves and energized by said power source whenever the corresponding return valve is open, and a normally open interlock circuit including a warning device, said interlock relays being energized to close said interlock circuit and actuate said warning device whenever both of said return valves are open simultaneously as a result of incomplete filling of a reservoir on the intake stroke of its respective system.

6. An hydraulic pressure exchange pump as defined in claim 1, wherein said pumping fluid control means includes an electric circuit and a source of power for energizing said circuit, an interlock relay operatively associated with each of said return valves and energized by said circuit whenever the corresponding return valve is open, and a normally open interlock circuit including a warning device, said interlock relays being energized to close said interlock circuit and actuate said warning device whenever both of said return valves are open simultaneously as a result of incomplete filling of a reservoir on the intake stroke of its respective system.

7. An hydraulic pressure exchange pump as defined in claim 1, wherein said pumping fluid systems are driven simultaneously by a single electric motor and said pumping fluid control means includes an electric circuit, including said pump motor, and a source of power for energizing said circuit; a latching relay for each pumping fluid system controlled by said high and low level responsive means in the respective system reservoirs, a

three-way solenoid operated control valve for each of said fluid motor operated return valves, said latching relays having latching and unlatching solenoids and normally open switch contacts controlled by said relay solenoids, 5 said contacts being in circuit between said power source and the solenoids operated of the respective solenoid control valves, whereby fluid pressure is delivered to said return valves only when said latching relays are energized and latched, said low level responsive means in said reservoirs including switch means in circuit between said power source and the latching solenoid of the respective latching relay, said last switch means being closed to complete the circuit when the fluid in the respective reservoir reaches said predetermined low level; said control means also including a further latching relay having latching and unlatching solenoids, the latching solenoid of which is in electrical parallel with the latching solenoid of one of said first named latching relays and the unlatching solenoid is in electrical parallel with the latching solenoid of the other of said first named latching relays; a three-way solenoid operated control valve for each of said pump return valves, said further relay having switch contacts alternately connecting one or the other of the solenoids of said control valves to said power source; said high level responsive means including switch contacts closed in response to fluid reaching said predetermined high level to complete a circuit to said power source through the unlatching solenoid of the respective first named latching relay.
